(57) **CLAIM**

The ornamental design for a micro-channeling device, as shown and described.

DESCRIPTION

FIG. 1 is a perspective view of the micro-channeling device showing our new design;

FIG. 2 is a front-side view of FIG. 1;

FIG. 3 is a back-side view of FIG. 1;

FIG. 4 is a right-side view of FIG. 1;

FIG. 5 is a left-side view of FIG. 1;

FIG. 6 is a top view of FIG. 1;

FIG. 7 is a bottom view of FIG. 1; and,

FIG. 8 is a perspective view of the micro-channeling device of FIG. 1 in use showing integration with other system components.

The broken lines shown in FIGS. 1-8 on the micro-channeling device illustrate portions of the micro-channeling device that form no part of the claimed design.

The additional broken lines in FIG. 8 depict how the micro-channeling device may be integrated during use with a micro-needle tip assembly illustrating environmental subject matter that forms no part of the claimed design.
